UNITED STATES PATENT OFFICE.

HENRY T. HAZARD, OF LOS ANGELES, CALIFORNIA.

SUSPENDERS.

SPECIFICATION forming part of Letters Patent No. 700,921, dated May 27, 1902.

Application filed December 4, 1901. Serial No. 84,676. (No model.)

To all whom it may concern:

Be it known that I, HENRY T. HAZARD, a citizen of the United States, residing at Los Angeles, in the county of Los Angeles, State of California, have invented new and useful Improvements in Suspenders, of which the following is a specification.

The objects of my invention are to provide a suspender that will hold the trousers well up in front and not unduly elevate them in the rear, that will become loose and slack when the wearer sits down, stoops, or bends over, and thereby avoid strain on the trousers while the wearer is in these positions, prevent undue wear on the seat, bagging at the knees, and pulling off the buttons, that can be easily attached to and detached from the trousers without any unbuttoning and will at all times give the wearer ease and comfort. I accomplish these objects by means of the improvements herein described and shown in the accompanying drawings, in which—

Figure 1 is a view of a pair of suspenders embodying my invention. Fig. 2 is an enlarged view of the cast-off mechanism, taken from the opposite side to that shown in Fig. 1.

In the drawings, A represents the shoulder-straps sewed together at the back. The leather binding-strap A' forms a fastening to secure the metallic attaching-loop G to the shoulder-strap. The shoulder-straps are connected with the back and side buttons by means of the equalizing-cord B. This cord passes from the button-loop C, on the end thereof, through eyelet-tube D, thence down to and through the eyelet-tube D', thence up to the fastening E, thence down to and through the other eyelet-tube D', thence up through the other eyelet D, and terminates in the other button-loop C. The button-loops C are for buttoning to the side buttons of the trousers, while the button-loops C', secured to the eyelet-tubes D', are for buttoning to the back buttons. The clasps on the fastenings E and the eyelet-tubes D are attached to the cast-off ring or loop F, and form, with the eyelet-tubes, a connection between the equalizing-cord B and the cast-off ring. This ring, which may be oval in shape, as shown in Fig. 1, or round, as in Fig. 2, together with the snap cast-off hook H, constituting part of the metallic loop G, form a cast-off connection between the

shoulder-straps and the equalizing-cord. The cord is permitted to move freely through the eyelets and adapt itself to any position of the body, while it returns readily to its normal position. In this way the greatest freedom of motion is allowed to the wearer without undue strain upon the shoulder-straps or cords or buttons or trousers. Although the cords and straps are non-elastic, they will accommodate themselves to the movement of the body without causing the least annoyance or inconvenience, giving ease and comfort to the wearer, as all unequal strain is compensated for by a ready paying out or taking up of the equalizing-cord.

It will be seen that in the absence of a cast-off mechanism it would require the unbuttoning of four buttons to release the trousers from the suspenders at the rear, which would be objectionable, to avoid which I employ a cast-off for easily attaching to and detaching the shoulder-straps from the trousers without any unbuttoning. To disconnect the shoulder-straps, the wearer first disconnects them in front, then passes both thumbs around the back into engagement with the back eyelet-tubes D' or with the equalizing-cord adjacent thereto and presses firmly down on the equalizing-cord until the cast-off ring F at the ends of the shoulder-straps is within easy reach of the hand, when a slight twist of the ring will disconnect it from the cast-off hook. The vest of the wearer will prevent the shoulder-straps from being pulled over and off the shoulders when being pulled down in the rear, as above stated, as the cast-off ring will be within easy reach of the hand before the front ends of the straps are well up on the shoulders. The straps are left in this depressed position until it is desired to reattach them to the trousers, when the cast-off ring is easily reattached to the hook. It will be manifest that there can be no strain on any of the parts while the wearer is stooping or sitting, because when the wearer bends forward, as he does in stooping or sitting, the eyelet-tube at the back end of the shoulder-straps moves in the direction of the side buttons, imparting a slack to the equalizing-cord, and thereby lengthening the suspenders, which will increase just in proportion as the wearer stoops forward.

Having described my invention, what I claim as new, and desire to secure by Letters Patent, is—

1. The combination with a pair of shoulder-straps secured together at their rear ends, and having attached thereto a snap-hook; a cast-off ring adapted to engage said hook, having secured thereto cord-engaging eyes; back tabs, having button-loops at their lower ends for engaging the back buttons, and having cord-engaging eyes on their upper ends; and an equalizing-cord, having button-loops for engaging the side buttons; the said cord passing from the side buttons up to and through the eyes on the cast-off loop, then down to and through the eyes on the back button-tabs, then up into a fastening on the cast-off loop; the said cord adapted to render freely through said eyes.
2. A pair of suspenders provided at their rear with a hook, a cast-off ring or loop, eyelet-tubes connected with the ring or loop, an

equalizing-cord adapted to render freely through the eyelets, rear tabs provided at their lower ends with button-loops to button 25 to the rear trousers-buttons and having at their upper ends eyelets adapted to receive the equalizing-cord and to permit the same to render freely therethrough, the equalizing-cord having button-loops for securing it to the 30 side buttons.

3. The combination of the shoulder-straps, loop G connected thereto, cast-off ring or loop F detachably connected thereto, said cast-off ring or loop having eyelets thereon, equalizing-cord passed loosely through said eyelets, and button-loops C, C, attached to the cord and loops D', D', loosely connected with the cord.

HENRY T. HAZARD.
